United States Patent Office

Des. 182,114
Patented Feb. 18, 1958

182,114

DISH OR SIMILAR ARTICLE OF HOLLOWWARE

Erich Fritsch, Clinton, and David Rauch, Worcester,
Mass., assignors to Van Brode Milling Co., Inc., Clinton,
Mass., a corporation of Massachusetts

Application February 6, 1956, Serial No. 40,041

Term of patent 7 years

(Cl. D44—15)

Fig. 1

Fig. 3

Fig. 1 is a front elevation of a dish or similar article of hollowware, showing our new design;

Fig. 2 is a side elevation of the same; and

Fig. 3 is a top plan view thereof.

We claim:

The ornamental design for a dish or similar article of hollowware, as shown.
